UNITED STATES PATENT OFFICE.

PONTALBA L. NASH, OF HOLLISTER, CALIFORNIA.

GRAIN-SEPARATOR FOR THRASHING-MACHINES.

SPECIFICATION forming part of Letters Patent No. 295,668, dated March 25, 1884.

Application filed December 7, 1883. (No model.)

To all whom it may concern:

Be it known that I, PONTALBA L. NASH, of Hollister, county of San Benito, and State of California, have invented an Improvement in 5 Grain-Separators for Thrashing-Machines; and I hereby declare the following to be a full, clear, and exact description thereof.

My invention relates to certain improvements in thrashing-machines; and it consists 10 in certain details of construction, which will be hereinafter more fully explained, and specified in the claims, reference being had to the accompanying drawings, in which—

Figure 1 is a longitudinal vertical section of 15 my apparatus. Fig. 2 is a transverse vertical section of the grain-table. Fig. 3 is a transverse vertical section of the apparatus through 12.

a is the frame-work of a thrashing-machine, 20 the upper part of which may be made somewhat higher than usual to accommodate the additional parts.

A is the thrashing-cylinder, to which the unthrashed straw may be fed in any suitable 25 or well-known manner. Above and behind the cylinder the top of the machine forms an arch, as shown at b, so that the straw may follow the curve after it leaves the cylinder and pass back to the rear of the machine, while 30 whatever grain is separated in the cylinder will fall through the straw-carrier B upon the inclined table C, by which it is brought back toward the front of the machine. This table is made higher in the center than at the edges, 35 like a roof, and the grain is thus caused to flow off into the troughs formed upon each side by the turned-up edges C', as shown in Fig. 2. The sides of the machine d come down inside these flanges C', and thus prevent the chaff 40 from being blown out at the sides. As this table has an incline downward toward the front, it will be seen that grain will flow down into the troughs at each edge, and the vibrating motion given the table by the rocker-arms 45 D causes it to move down to the point of discharge just in front of the fan E and upon a carrier-belt, F, by which it is delivered upon a table and riddle, G G'. The table G and riddle G' are continuous, and the sieve N is 50 fixed to the riddle just beneath it, the whole moving together. The arm D has its center

pivoted to the frame, the upper being end connected with the table C and the lower end with the table G, which is suspended by the links m, as shown. The force with which the grain and straw are thrown back from the cylinder causes the former to follow the arched top back nearly to the rear end, where it falls upon the table, as before described; but in this instance I fix a sheet of metal about twelve inches wide above and behind the cylinder, and by bending this the grain may be given any desired direction as it leaves the cylinder. The straw falls upon the carrier B, by which it is returned so as to pass down in front of the center of the fan E, the blast from which turns it again toward the rear, and it falls upon the second straw-carrier, K, which carries it toward the rear end of the machine again.

d is a curved shield, which serves the double purpose of deflecting, with its convex surface, the grain and straw from the cylinder into the upper part of the machine, as before described, and its concave surface directs the grain and straw which are returning toward the front downward and backward again.

ff are inclined strips placed within or near this concave shield, and they serve to keep the straw in the center and deliver it in this manner upon the carrier K below.

I is a fan situated at the upper rear end of the machine, and a curved air duct or passage, J, extends from it above the arched top of the machine. The bottom of this duct is open or perforated with holes at i, which allow the air-blast to pass through and into the space beneath the arch, so as to force the straw downward upon the return-carrier B, and also to partially separate the grain from it. Any grain which may be separated from the straw while passing over the carrier K will fall through upon the belt F below, to be carried with the larger quantity to the table G, before mentioned. This table is in the same plane with riddle or screen G', and the grain and chaff which fall upon it are carried forward by the end-shaking motion which it receives from the crank or eccentric g, and pass upon the screen, where the work of separation begins. The straw falls from the second straw-carrier, K, upon the carrier L, by which it is discharged at the rear of the machine.

M is another fan opening toward the rear, so that all straw which falls from K to L will be subjected to a blast of air from it, and a further separation of any grain in it will take place. From the perforated riddle G the grain falls through upon the sieve N, where it is subjected to a blast of air from the fan O. The grain falls through upon the incline P and slides down to the auger Q, by which it is taken to the side of the machine to be sacked. The blast from the fan blows the chaff out at the rear of the machine. The heavier barley and unthrashed heads of wheat will be stopped by a board, R, and will fall into the auger S, by which it is carried to one side and to the return-elevator.

T is a vertical board or stop at the rear of the sieve-frame, and by this any bolt, nut, or tooth which may become loosened will be stopped when it reaches this point and prevented from falling into the auger S, to be returned by the elevator and again pass through the cylinder.

At the outer end of the auger Q is an extension or supplemental auger, U, which may be connected with the shaft of the auger Q by a universal joint, V, so that the secondary auger will be driven from it. The universal joint allows the end of this auger to be raised to any desired height, and it will thus elevate the grain to a point high enough to be sacked, which is done by the double chute and direction-gate shown in Fig. 4. The various carrier-belts, fans, and other devices are driven by belts in a manner similar to that usually adopted in this class of machines. The upper grain-table and the screen-frame are caused to vibrate end-wise by means of the rocker-arm D and a crank or eccentric connection, as at W. Any grain which falls directly from the thrashing-

cylinder is received upon a belt, g, and is carried up by it beneath the shield d and delivered behind the fan E and falls upon the belt F. 40

Having thus described my invention, what I claim as new, and desire to secure by Letters Patent, is—

1. In a thrashing-machine, the thrashing-cylinder, in combination with a directing-shield, d, the arched top b, the blast-fan, and duct J, substantially as herein described. 45

2. In a thrashing-machine, the combination, 50 with the thrashing-cylinder, of the arched top, forming a space through which the grain and straw may be projected from the cylinder, the superposed air-duct, the blast-fan, the inclined angular grain-table, and the return-carrier B, 55 substantially as herein described.

3. The inclined angular grain-table, the suspending-links and end-shaking mechanism, and the return straw-carrier traveling above the table, in combination with the curved shield 60 d, inclined directing-strips, and the fan E, substantially as herein described.

4. The inclined angular shaking-table, the return straw-carrier, directing-shield and strips, and the fan E, in combination with the straw-carrier K and grain-belt F, substantially as herein described. 65

5. The combination of the inclined angular shaking-table, the return straw-carrier, directing-shield, carriers K and L, fans E and M, 70 grain-belt F, and the screens, substantially as herein described.

In witness whereof I have hereunto set my hand.

PONTALBA L. NASH.
